UNITED STATES PATENT OFFICE.

CHARLES S. WEBER, OF SAN JOSE, CALIFORNIA.

PIN FOR PIANO-BRIDGES.

1,011,536.

Specification of Letters Patent. Patented Dec. 12, 1911.

Application filed November 28, 1910. Serial No. 594,581.

To all whom it may concern:

Be it known that I, CHARLES S. WEBER, citizen of the United States, residing at San Jose, in the county of Santa Clara and State of California, have invented certain new and useful Improvements in Pins for Piano-Bridges, of which the following is a specification.

This invention comprehends certain new and useful improvements in pianos and relates particularly to bridge pins designed to produce a deflection of the strings as they meet and leave the surface of the sounding board bridge from which they pass, and the invention has for its primary object an improved construction of bridge pin whereby the strings may be securely held in place and an increased deflection secured without any danger of splitting or otherwise impairing the fibers of the wooden bridge and without any danger of the pins becoming loose, while at the same time a positive advantage is secured in that the increased deflection and the firm engagement by which the strings are held, by my improved bridge pins, in contact with the bridge surface over which they extend, result in a singing and mellow tone, giving a well defined pitch.

Expressed in another way, my invention has for its primary object improved construction of bridge pins capable of sustaining the pressure arising from a greater angle of deflection of the string than it has heretofore been practicable to give musical strings, when secured only by means of the ordinary straight shank deflecting pins heretofore used for securing the strings to the surface of the bridge of a sounding board.

In the ordinary pianos, as heretofore constructed, the maximum deflection of the strings has already been determined, that is, the amount of deflection that can be safely supported by the usual bridge pin held in a wooden bridge, and with a knowledge of these conditions and to support the pressure resulting from an increased angle of deflection, my invention, in one aspect, consists in joining together the upper ends of two or more bridge pins; and in another aspect, consists in pins of this character in which the string engaging surfaces of the pins are either divergent or convergent. The mere joining of said ends, as I have already proven by actual experiment and demonstration, results in a perceptible gain in the

stability of the pin at its point of contact with the deflected string; and the still more important result is obtained by so joining the ends of two or more bridge pins, that the deflecting or string engaging faces thereof will be convergent or divergent, when it will be found that the lateral pressure of two deflected strings will be almost completely neutralized inasmuch as they press against the device in opposite directions. And the invention also consists in certain constructions and arrangements of the parts that I shall hereinafter fully describe and claim, it being understood, of course, that in the preferred embodiment of the invention, I mean, when I state that I join together two bridge pins, I make a bridge pin, as a complete article of manufacture in itself, ready for use, but in a sense two pins joined together at their upper ends by a connecting bar, although the device, it is to be understood, is manufactured with such bar as a part of it; and it is not to be understood that two or more ordinary single shank bridge pins are joined together either before or after being applied to the bridge of a sounding board, to produce the preferred embodiment of my invention, even though, as a matter of fact I claim that my invention is of a scope sufficient to embrace such joining.

For a full understanding of the invention, reference is to be had to the following description and accompanying drawings, in which:

Figure 1 is a top plan view of a portion of a sound board bridge, showing the average and exceptional deflection used with bridge pins as heretofore ordinarily constructed; Figs. 2, 3, 4 and 5 are fragmentary longitudinal sectional views, illustrating different forms of my improved bridge pin; Fig. 6 is a top plan view illustrating an arrangement of the forms illustrated in detail in Figs. 2 and 3 combined; Figs. 7 and 8 are top plan and cross sectional views, respectively, illustrating means for binding two of the bridge pins together; Fig. 9 is a top plan view illustrating the preferred three-string arrangement; and, Fig. 10 illustrates another embodiment of my invention, the strings being crossed as they pass over the bridge.

Corresponding and like parts are referred to in the following description and indicated in all the views of the drawings by the same reference characters.

Referring to the drawing, the numeral 1

designates a portion of a sound-board bridge, and 2 designates a string extending across said bridge, said string being deflect-
 5 ed by the ordinary bridge pins 3, the string
 to the left showing the ordinary angle of
 deflection, and the string at the right show-
 ing an exceptional amount of deflection, be-
 yond which it is not expedient to go with
 10 the ordinary bridge pins, although numer-
 ous experiments have led me to the conclu-
 sion that by increasing the angle of deflec-
 tion in the string over the bridge of the
 sound board, the quality of the tone is im-
 15 proved. However, it is obvious that the
 angle of deflection may be great and the
 resulting tone poor, as for instance when
 the great pressure of the deflected strings
 tears or otherwise impairs the wood fibers
 20 that sustain the deflecting pins, and hence,
 with the ordinary bridge pins, as heretofore
 constructed, it has not been safe to increase
 the angle of deflection beyond that indicated
 in Fig. 1, as exceptional, while in nearly
 25 every case the average angle of deflection
 shown by the string to the left in Fig. 1,
 has been adhered to.

In carrying out my invention and in con-
 tradistinction to bridge pins as heretofore
 ordinarily constructed, reference is to be
 30 had to Figs. 2 to 5, wherein several forms
 of my invention are illustrated. In the
 form shown in Fig. 2, two shanks are joined
 by a connecting bar 4 so that the deflecting
 35 or string engaging faces or edges 5 of the
 pin will be convergent, 2 designating the
 strings. In that form illustrated in Fig. 3,
 in which 4^a designates the connecting bar,
 the deflecting faces 5^a are divergent. In
 40 those forms illustrated in Figs. 5 and 4, two
 and three pins, respectively, are joined. On
 the same principle, I may use the one form
 of my improved bridge pin with another,
 and may, if found desirable or necessary,
 45 particularly where the deflection in the
 strings is carried to a very high degree, when
 a resultant force will tend to separate one of
 my improved pins from the other, I may
 join one device to the other. For instance,
 50 as illustrated in Fig. 6, I may use that form
 of the invention illustrated in Fig. 2 in con-
 nection with that form illustrated in Fig. 3,
 and may also, as illustrated in Figs. 7 and 8,
 where a very large angle of deflection is
 55 shown, connect one device with the other.
 It is to be understood that no rigid connec-
 tion will be necessary, a few strands of
 twine, (may be moisture proof) and design-
 ated 6, being generally sufficient to hold
 60 the two devices together and avoid all dan-
 gers of splitting the bridge. In viewing
 Figs. 6 and 7, it will be noted that in Fig. 7
 a stronger deflection of the strings is indi-
 cated than is shown in Fig. 6.

Fig. 9 shows my invention in connection
 65 with the ordinary bridge pins, in order to

illustrate my arrangement of three strings to
 a note, two strings being arranged according
 to my improvements, and one according to
 the old method, it not being convenient (al-
 though possible) to use my invention on an 70
 odd number of strings. It is customary and
 proper to have in the treble three unisons
 (strings) to each note and as just indicated
 I have found it most convenient to use the
 75 ordinary bridge pin for the third unison;
 but it will be noted by particular reference
 to Fig. 9 that the third string, namely, the
 one held deflected by the ordinary bridge
 pins, has a smaller angle of deflection, than
 80 those deflected by my improved double pins.

Fig. 10 illustrates a combination of two
 bridge pins of the form illustrated in detail
 in Fig. 3. This arrangement is only appli-
 cable in my judgment to the thinner strings
 85 of the higher notes and even there it is pref-
 erable to press the lowermost string into the
 wood to avoid the top string being lifted
 above the surface of the bridge, and result-
 ing in a metallic tone.

From the foregoing description in connec- 90
 tion with my accompanying drawing, it will
 be seen that I have provided a very simple
 and efficient construction of bridge pin
 which will admit of a much greater angle
 95 of deflection being given to the strings, than
 has heretofore been found practicable with
 the use of bridge pins, while at the same
 time my invention maintains the strings in
 firm contact with the wood of the bridge
 100 throughout the passage of the strings over
 the bridge, resulting in mellow tones com-
 bined with singing quality of the highest
 degree, as well as trueness of pitch.

Having thus described the invention, what
 is claimed as new is:

1. A piano having a bridge, strings pass-
 ing over said bridge, and bridge pins se-
 cured to said bridge at opposite edges there-
 of, each pin having more than one deflecting
 110 edge, each of which engages one unison, the
 deflecting edges of one pin slanting trans-
 versely of the strings which they engage in
 a direction opposite to the corresponding
 edges of the adjoining opposite pin.

2. A piano having a bridge, strings pass-
 ing over said bridge, and bridge pins se-
 cured to said bridge and each having more
 than one deflecting edge each in contact with
 a musical string, the deflecting edges of two
 115 adjoining pins slanting transversely of the
 strings in opposite directions, each engaging
 one of the unisons and holding said unisons
 deflected in opposite directions.

3. A piano having a bridge, strings pass-
 ing over said bridge, and bridge pins secured
 to said bridge and embodying shanks driven
 into the bridge and a connecting bar spaced
 from the adjoining face of the bridge and
 joining said shanks together, each pin hav-
 125 ing more than one deflecting edge each in
 130

contact with a string and extending over the string, the deflecting edges of two adjoining pins slanting transversely of the strings in opposite directions, each holding one of the

5 unisons deflected in opposite directions and firmly pressing the string which it engages down upon the bridge.

4. A piano having a bridge, strings passing over said bridge, and bridge pins secured to said bridge, each pin embodying two shanks and a connecting bar joining said shanks together, the shanks being secured to the bridge and provided with more than one deflecting edge, each edge in contact with a musical string and slanting transversely of the string, so as to extend partially there-around.

5. A piano, having a bridge, strings passing over said bridge, bridge pins secured to the bridge at opposite edges of the latter, said pins being provided with slanting edges

engaging the strings and holding the same deflected, and a connection between the pin on one side of the bridge and a pin on the opposite side of the bridge. 25

6. A piano having a bridge, strings passing across the bridge, and bridge pins secured to the bridge at opposite edges thereof, each of said pins embodying two shanks and a connecting bar joining one shank to 30 the other, each of said pins being formed with more than one string engaging edge, each in contact with a string and holding the same deflected, and a connection between the pin on one side of the bridge and a pin 35 on the opposite side of the bridge.

In testimony whereof, I affix my signature in presence of two witnesses.

CHARLES S. WEBER. [L. S.]
